UNITED STATES PATENT OFFICE.

PETER A. DEASY, OF OAKLAND, CALIFORNIA, ASSIGNOR TO DEASY UTILITIES COMPANY, OF OAKLAND, CALIFORNIA, A CORPORATION.

WATER-HEATER.

1,122,578.

Specification of Letters Patent. Patented Dec. 29, 1914.

Application filed February 3, 1913. Serial No. 745,915.

To all whom it may concern:

Be it known that I, PETER A. DEASY, a citizen of the United States, residing at Oakland, in the county of Alameda and State of California, have invented certain new and useful Improvements in Water-Heaters, of which the following is a specification.

This invention relates to water heaters, and one of the objects is to provide the heater with an improved type of coupling between the heating coil and the boiler, whereby circulation will be permitted.

Another object of the invention is to so construct this connection that the heating coil may be very readily disconnected from the boiler.

Another object of the invention is to provide a novel construction whereby the products of combustion from the heating elements will be prevented from passing directly out of the lower portion of the boiler.

Another object of the invention is to so construct the lower portion of the boiler that the heating chamber will be surrounded by a water jacket thereby causing the water to be quickly heated.

With these and other objects in view this invention consists of certain novel combinations, constructions, and arrangements of parts as will be hereinafter fully described and claimed.

In the accompanying drawings:—Figure 1 is a view of the improved boiler shown partially in elevation and partially in vertical section. Fig. 2 is a sectional view through the coupling which connects the heating coil with the boiler. Fig. 3 is a view similar to Fig. 1 showing a slightly modified form of boiler. Fig. 4 is a sectional view through the coupling shown in Fig. 3. Fig. 5 is a fragmentary view of the flue which passes through the boiler.

Referring to Figs. 1, 2, and 5 it will be seen that this boiler comprises a casing 10 having the top 11 and bottom 12, thus forming the water chamber 13. This boiler is provided with the cold water inlet pipe 14 and with a hot water draw-off pipe 15, which is positioned adjacent the flue 16 located to one side of the vertical center of the boiler. From an inspection of Fig. 5 it will be seen that the flue is provided with a crimped section 17, thus permitting the flue to expand and contract without any

danger of straining the boiler and causing it to leak. It is, of course, obvious that when the products of combustion are passing through this flue that the flue will be heated to a greater extent than the top and bottom 60 of the boiler and, therefore, if it were not for this crimped portion the boiler would be liable to be strained. A circulating pipe 18 is centrally located in the boiler and is held in place by a packing nut 19 in threaded engagement with the lower end portion of the pipe 18, and with a collar 20 formed upon the bottom 12 of the boiler. A drip pan 21 is secured to the bottom of the boiler and is positioned beneath the flue 16 so that 65 water formed from condensation in the flue will be caught and thus prevented from dripping. It is, of course, obvious that when the heating element is in operation that this drip pan will be heated and the 70 water in it thus evaporated. This boiler is provided with a lower portion 22 forming a heating chamber, and also forming a support for the boiler by having its upper portion 23 reduced to form a neck about which 75 the lower portion of the boiler fits as clearly shown in Fig. 1. This heating chamber is supported by the usual floor-stand 24 and is provided with a door 25 to permit access to the interior of the heating chamber. A 80 gas burner 26 is positioned in the heating chamber and is fed by a valve control gas pipe 27 having a pilot pipe 28 leading therefrom. This pipe 28 extends into the heating chamber above the burner 26, thus permitting the burner to be easily lighted. From an inspection of Fig. 1 it will be 85 readily seen that this burner is positioned out of alignment with the flue 16 and, therefore, the products of combustion will not 90 pass directly out through the flue but must remain in the heating chamber for a short time before passing out. Therefore, the 95 heating coil positioned in the heating chamber will be heated more readily and, therefore, the water will be very quickly heated. This heating coil 29 has one end threaded 100 into the lower end of a coupling 30 and has its other end brazed into an arm 31 leading from the coupling 30. A short pipe 32 is 105 positioned in the coupling 30 with its lower end portion threaded into the lower portion of the coupling. This pipe is of less diameter than the interior of the coupling and extends up into the pipe 18 with its upper 110

end provided with a bushing 33 holding the pipe in the proper position and preventing water from passing downwardly through the pipe 18. Openings 34 are formed in the pipe 18 beneath the bushing 33 so that the cold water in the lower portion of the boiler may pass through the opening 34 into the space surrounding the pipe 32 and through the arm 31 into the coil 29. This will then pass through the coil where it is heated and then travels through the pipe 32 into the pipe 18 above the bushing 33. It then passes out of the upper end of the pipe 18 into the upper portion of the boiler where it may be drawn out through the pipe 15. The coupling 30 is supported by having its upper end portion threaded and engaged by a union 35 rotatably mounted upon a nipple 36 having its upper end portion threaded and screwed into the packing nut 19.

From the above description it will be readily understood that the boiler is filled by water entering through the pipe 14 and that the water in the boiler passes through the openings 34 into the space surrounding the pipe 32 and then passes through the coil 29 and up through the pipe 32 into the pipe 18 from which it is emptied into the upper portion of the boiler. The hot water in the top of the boiler can then be drawn out through the pipe 15. It should be noted that this pipe 15 is located near the flue 16 and that, therefore, the water which is drawn out will be kept very hot since the products of combustion pass therethrough thereby constituting an additional means for heating the water in the boiler.

In Figs. 3 and 4 there has been shown a slightly modified form of boiler. In this form the casing 37 is mounted directly upon the floor support 38 and has its bottom 39 connected with a lining 40 having its lower edge portion secured to the casing, but having its remaining portion positioned in spaced relation to the casing, thus leaving a space 41 forming a water jacket. This boiler is provided with the water inlet pipe 42, the draw-off pipe 43, and flue 44 similar to the construction shown in Fig. 1 and is also provided with a drip pan 45. The burner 46 is similar in construction to the burner 29 and is fed by a valve control pipe 47 from which there leads a pilot pipe 48. The heating coil 49 has its inlet end communicating with the lower portion of the water jacket and has its outlet end connected with the pipe 50 by the coupling shown in Fig. 4. This pipe 50 is held in place by a packing nut 51 in threaded engagement with a collar 52 and communicates with a nipple 53 having a threaded lower end portion so that the sleeve 54 mounted upon the outlet end of the coil 49 may be connected with the nipple 53 by the union 55 rotatably mounted upon the sleeve

54. In this form of boiler the water will be very quickly heated since the water jacket is comparatively narrow and, therefore, the water will be partially heated before it enters the inlet end of the coil. In this form as well as in the form shown in Fig. 1 the heating coil can be very readily disconnected from the boiler since it is only necessary to unscrew the union 55 when it is desired to remove the coil. In connection with Fig. 1 it should be noted that the water entering the coil will be partially heated since it passes into the narrow space between the coupling 30 and pipe 32 and will, thus be heated by the hot water in the pipe 32 and by the products of combustion in the heating chamber.

Having thus described the invention what is claimed as new, is:—

1. A boiler comprising a water chamber, a heating chamber positioned beneath said water chamber, a pipe extending through said water chamber, a coupling connected with the bottom of said water chamber and communicating with said pipe, a pipe extending through said coupling into said first mentioned pipe and having its upper end closing the lower end portion of said first mentioned pipe above openings formed therein, a coil positioned in said heating chamber and having its ends communicating with said coupling whereby water may pass through the openings in said first mentioned pipe into said coupling and then through said coil into the pipe extending through said coupling into said first mentioned pipe, and heating means in said heating chamber.

2. In a boiler, a water chamber, a pipe extending into the water chamber and provided with inlet openings adjacent its lower end, a coupling connected with the lower end portion of said pipe, an arm extending from said coupling, a heating coil having one end communicating with the arm of said coupling and having its other end communicating with the lower end portion of said coupling, and a pipe of less diameter than the interior of said coupling extending from the lower end portion of said coupling into said first mentioned pipe and forming a closure for the lower end portion of said first mentioned pipe above the openings formed therein.

3. In a boiler, a water chamber, a bottom for said water chamber having an opening formed therein and having an internally threaded collar surrounding the opening, a pipe positioned in said water chamber and having its lower end portion provided with inlet openings, a packing nut engaging the lower end portion of said pipe and screwed into said collar, a nipple screwed into said packing nut, a heating coil, a coupling connected with the ends of said heating coil, a

union connecting said coupling with said nipple, a pipe of less diameter than the interior of said coupling having its lower end portion connected with the lower portion of said coupling and communicating with one end of said coil, the upper end portion of said last mentioned pipe extending into said first mentioned pipe, and a bushing mounted upon the upper end portion of said second mentioned pipe for closing the space

between said first mentioned pipe and the upper end portion of said second mentioned pipe.

In testimony whereof I affix my signature in presence of two witnesses.
